(57) **CLAIM**

The ornamental design for a multi-piece tactical gear belt mount, as shown and described.

DESCRIPTION

FIG. 1 is a front perspective view of a first embodiment of a multi-piece tactical gear belt mount showing our new design; FIG. 2 is a top view thereof;

FIG. 3 is a bottom view thereof;

FIG. 4 is a front view thereof;

FIG. 5 is a back view thereof;

FIG. 6 is a right side view thereof;

FIG. 7 is a left side view thereof;

FIG. 8 is a front perspective view of the embodiment shown in FIG. 1 in a separated configuration;

FIG. 9 is a top view thereof in the separated configuration;

FIG. 10 is a bottom view thereof in the separated configuration;

FIG. 11 is a front view thereof in the separated configuration;

FIG. 12 is a rear view thereof in the separated configuration;

FIG. 13 is a right side view thereof in the separated configuration; and,

FIG. 14 is a left side view thereof in the separated configuration.

The broken line portions showing webbing in FIGS. 1-14 are shown to illustrate environment only and form no part of the claimed design.
